MATERNITY DRESS

Verna G. Hager, 1 Delaware St., Conrad, Mont.

Filed Dec. 4, 1963, Ser. No. 77,673

Term of patent 14 years

(Cl. D3—26)

FIG. 1.

FIG. 2.

FIG. 3.

FIG. 5.

FIG. 4.

FIG. 6.

FIG. 1 is a front perspective view of a maternity dress, showing my new design;

FIG. 2 is a rear perspective view thereof;

FIG. 3 is another front perspective view thereof, illustrating the pleats in a partially expanded position;

FIG. 4 is an enlarged cross-sectional view taken on the line 4—4 of FIG. 3;

FIG. 5 is a fragmentary perspective view of the upper portion of the maternity dress shown in FIG. 3 illustrating the slide fastener and the pleats on the right side thereof in untied position; and

FIG. 6 is a front elevational view of a maternity dress showing my new design.

The present application is a continuation-in-part of my copending application Serial No. D. 70,290, filed May 24, 1962, and now abandoned.

I claim:

The ornamental design for a maternity dress, substantially as shown and described.
